POULT FEED SAVER

Melvin J. Luse, Moville, Iowa

Application December 30, 1949, Serial No. 135,881

1 Claim. (Cl. 119—61)

1

My invention relates to a poult feed saver.

An object of my invention is to provide a feed saver wherein the feed eaten by the poult will not become lost outside of the feed trough but will fall back into the trough, thereby conserving a great deal of feed throughout the season.

A further and important object of my invention is to provide an arrangement which is simple to detach and clean, the removable portions of which can also be readily replaced.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a plan view of the feed saver,

Figure 2 is a side elevation of Figure 1,

Figure 3 is an enlarged sectional view taken 20 along the lines 3—3 of Figure 1, and

Figure 4 is a detail.

I have used the character 10 to designate the two end supports of my feed saver, these members 10 extending into the feet 11, the members 10 continuing into the further portions 12 including the cut-away portions at 13, which portions include the slots 14 for the reception of the small rods 15 at various heights desired, and attached to the pins 15 is the rotating paddle-like structure 16 which prevents the fowl from remaining thereon due to the rotation thereof.

Attached to the ends 10 is a substantially semi-cylindrical trough member 17 terminating in the curled upper portions 18. Bent out of the material of the members 10 are the small ears 19 which are so arranged as to snugly receive the arcuate partitions 20, the partitions 20 being spaced from the member 17 as shown. The partitions 20 include the small ears 21 bent therefrom so that when the partitions are put in place between the ears, the ears 21 will support them.

The feed is placed in the trough within the partitions 20 and being supported by means of the lower portions of the trough 17.

When the creatures feed, any of the feed which spills over between the partitions 20 and the trough 17 will be carried downwardly by virtue of the curved surface of the trough 17 toward the bottom, thereby conserving the feed, which can be reused.

2

It will be noted that the partitions by virtue of this simple structure can be readily removed and re-placed for cleaning and the like, and it will also be noted that the arcuate passageways provided by this structure insure that the feed will gravitate naturally in an efficient manner.

It will now be seen that I have provided the various advantages set forth in the objects of my invention with various other advantages being 10 readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within its scope.

I claim as my invention:

A poult feed saver comprising a semi-cylindrical trough, a pair of arcuate partitions concentric with said cylindrical trough and inwardly spaced therefrom for providing substantially arcuate passageways for feed spilled over said arcuate partitions, there being an open space at the bottom of said partitions to provide means for containing feed in said trough, end members attached to said trough, said end members having ears struck outwardly therefrom, said ears lying adjacent to said arcuate partitions for allowing removal and insertion of said partitions, said partitions having ears extending therefrom for bearing against said end ears to support said partitions.

MELVIN J. LUSE.
